UNITED STATES PATENT OFFICE.

ALBERT BUCEY, OF BOWERSTOWN, OHIO.

MINE APPARATUS.

1,294,868.

Specification of Letters Patent. Patented Feb. 18, 1919.

Application filed May 14, 1918. Serial No. 234,462.

To all whom it may concern:

Be it known that I, ALBERT BUCEY, a citizen of the United States, residing at Bowers-
town, in the county of Harrison and State
5 of Ohio, have invented new and useful Im-
provements in Mine Apparatus, of which the
following is a specification.

This invention relates to an apparatus for
handling cars in a mine and more particu-
10 larly to an apparatus for feeding cars onto
and off of the cage and has for its primary
object to simplify and thereby reduce the
expense of an apparatus of this character.

An object of the invention is to provide an
15 apparatus in which only three stops can ac-
complish the work of the usual four stops
necessary in the apparatuses now in use.

Another object of the invention is to pro-
vide mechanism that may, without changes,
20 be attached to the top surface of a cage or
the under surface depending upon which is
the most advantageous in practice when used
on the different type cages now in use.

Besides the above my invention is dis-
25 tinguished in the use of cage mechanism and
trackway mechanism of substantially the
same construction for feeding cars onto the
cage and off the cage.

With these and other objects in view the
30 invention will be better understood from the
following detailed description taken in con-
nection with the accompanying drawings
wherein:

Figure 1 is a top plan view of a cage show-
35 ing my invention applied thereto.

Fig. 2 is a longitudinal sectional view.

Fig. 3 is a detail view of a portion of the
link mechanism. Fig. 4 is a sectional view
40 through a rail showing the rear stop in ele-
vation. Fig. 5 is a detailed view of the car
actuated lever. Fig. 6 is a top plan view of
the trackway mechanism. Fig. 7 is a de-
tailed view of one element of the clutch.
Fig. 8 is a detailed view of one of the stops.

45 Again referring to the drawings the num-
eral 1 designates a shaft consisting of two
parts 2 and 3, both mounted for rotatable
movement in bearings 4 while part 3 is also
mounted for longitudinal sliding movements.
50 One end of the shaft in this particular in-
stance the part 2, has connected thereto a
crank arm 5 adapted to strike a stationary
arm 6 within the mine when the cage 7
reaches predetermined positions.

55 A clutch device 8 is arranged to normally
connect the parts 2 and 3 together and in

this particular showing consists of two ele-
ments 9 and 10 connected respectively to the
associated ends of the parts 2 and 3. By in-
specting the drawings it will be seen that the 60
end of the part 3 projects beyond the element
10 and is mounted for sliding movement
within the element 9 thereby assuring proper
alinement of the lugs 11 on the confronting
faces of the elements 9 and 10. Mounted on 65
each of the parts 2 and 3 is a coil expansion
spring 12 having one end fixed to a collar 13
on the part and the other end fixed to one of
the bearings 4. By this arrangement it will
be seen that one of the coil expansion springs 70
12 performs a dual function of forcing one
part toward the other part and besides both
springs return the parts to normal position,
when partly rotated by the crank arm 5
striking the arm 6. The expandible action 75
of the spring 12 normally holds the clutch
elements in engagement with each other so
that the parts will move as a unit when pres-
sure is applied upon the crank arm 5. At
certain times it is necessary that the clutch 80
be rendered inoperative for accomplishing an
operation hereinafter described. For this
purpose I provide a car actuated lever 13
pivoted to a bracket 15 and further pivot-
ally connected to one end of a link 16 the 85
other end of which is forked as indicated at
17 and arranged behind the collar 13^a. For
the purpose of absorbing shock a spring 18
is arranged between the fork 17 and the ad-
jacent bearing 4. As far as I have proceed-
ed it will be seen that when the crank arm 5
strikes the arm 6 both parts of the shaft will
be rotated as a unit; whereas upon a car axle
striking the lever 14 the part 3 will be slid 90
longitudinally for disengaging the clutch
elements, thereby allowing the part 3 to ro-
tate independently of the part 2 by the tor-
sional action of the spring 12. Projecting
from the element 8 are arms 19. Pivotal-
ly connected to the rails are stops 20 and 21. 100
The stop 20 is connected to the arm 19 by a
link 22 and yieldably forced in a predeter-
mined direction by a spring 23. The stop 21
is connected to a second pivoted lever 24 by
a link 25. The lever 24 is also pivotally con-
nected by a link 26 to the arm 19. To com-
plete the cage mechanism I provide a third
pivoted stop 27 normally forced to an opera-
tive position by a leaf spring 28. This stop
27 is provided with a cam surface 29 so as 105
to be automatically forced to an inoperative
position in the passage of a car.

The track-way mechanism 30 is identical to that described with the following exceptions:

The crank arm 31 is constructed to be engaged by a descending cage. One part of the shaft has connected thereto a weight 32 normally holding the parts in predetermined positions. As an improvement over the cage mechanism the spring 33 of the trackway mechanism consists of two parts 34 and 35 each acting against a bearing 36 and a collar 37 fixed to the shaft. Working between the collars 37 is the forked end 38 of a link 35. The remaining parts of the trackway mechanism are identical to the cage mechanism with the exception that the element 40 of the clutch device is provided with diametrically arranged ears 41 pivoted to links 42 that are directly connected to the stops 43.

From the foregoing description taken in connection with the drawings it should be apparent that I provide a simple mechanism of substantial construction in which the parts are so arranged and constructed that the operation of the apparatus is assured, with a minimum number of parts.

It is of course to be understood that the

mechanism may be constructed in various other ways than that shown, which is illustrated in the simplest form, all mechanical details being eliminated. Therefore I do not desire to be limited to the exact showing exact showing except as set forth in the claim appended.

Having described my invention, what I claim is:

A mine car handling apparatus comprising a two part shaft, a crank rigidly connected to one end of the shaft, a clutch device consisting of two elements rigidly connected respectively to said parts, said parts being slidably related, car stopping and releasing means having a connection with one of the elements, a collar fixed upon one of said parts, a pair of coil springs mounted on said shaft and abutting a stationary support, one of said springs being capable of returning said shaft part which it is associated with to normal position, and a car operated pivoted lever engaging said collar between said springs for the purpose set forth.

In testimony whereof I affix my signature.

ALBERT BUCEY.
